Term of patent 14 years

Int. Cl. D8—07

U.S. Cl. D8—154

FIG. 1

FIG. 2

FIG. 3

FIG. 1 is a perspective view of a combined closure and handle for a carrier bag showing our new design;

FIG. 2 is an elevational view taken from one side thereof; and

FIG. 3 is an elevational view taken from the side opposite that shown in FIG. 2.

The fragmentary broken line representation of a carrier bag in FIGS. 1 through 3 is for purposes of illustration only.

This is a division of design application Ser. No. D. 16,328, filed Mar. 19, 1969, now Design Patent No. D. 217,712.

We claim:

The ornamental design for a combined closure and handle for a carrier bag, as shown and described.
